FRANCIS CARP.

BY Higdon & Langen, 1912.

UNITED STATES PATENT OFFICE.

ARTHUR CARP, OF ST. LOUIS, MISSOURI.

WRENCH.

1,042,531.

Specification of Letters Patent.

Patented Oct. 29, 1912.

Application filed June 17, 1912. Serial No. 704,112.

To all whom it may concern:

Be it known that I, ARTHUR CARP, a subject of the Czar of Russia, and resident of St. Louis, Missouri, have invented certain new and useful Improvements in Wrenches, of which the following is a specification containing a full, clear, and exact description, reference being had to the accompanying drawings, forming a part hereof.

10 My invention relates to improvements in wrenches, and the object of my invention is to construct a wrench provided with means whereby the movable jaw may be released and spring-pressed to an extended 15 position. The said releasing means is arranged in such manner as to permit of an adjustment of the sliding jaw to the finest degree, said releasing means being also arranged in such manner as to form a lock in 20 order to prevent a movement of the sliding jaw when in a closed position.

With the above purposes in view my invention consists in certain novel features of construction and arrangement of parts as 25 will be hereinafter more fully described, pointed out in the claims and illustrated by the accompanying drawings, in which—

Figure 1 is a longitudinal, sectional elevation of the complete wrench, the sliding jaw 30 being shown in a closed position; Fig. 2 is a view similar to Fig. 1 with the sliding jaw shown in an extended position; Fig. 3 is a transverse, sectional elevation taken on the line 3—3 of Fig. 1; and Fig. 4 is a trans- 35 verse, sectional elevation taken on the line 4—4 of Fig. 1.

Referring by numerals to the accompanying drawings: 5 designates the body or handle portion of the wrench which is preferably constructed of a single piece of metal in rectangular tube form, the handle being open at both of its ends and the outer forward corner of the handle is beveled off in order that the head 6 of the fixed jaw 45 may lie as closely as possible to the end of the handle. The said jaw is provided with an integral, rectangular shank 7 which is secured in the handle by means of rivets 8, or the like.

50 9 designates a cut away portion formed by removing portions of the side and front walls of the handle 5. This cut away portion extends from the inner end of the shank 7 of the fixed jaw and provides for the exposure of the adjusting screw 10 having

formed integral therewith a portion 11 provided with a knurled surface.

12 designates a block which is arranged adjacent the inner end of the handle and pivotally mounted upon a pin 13 in order that it may rock within the handle 5. The block 12 is provided with a longitudinal bore to receive the rod 14, the upper or forward end of which is seated in a depression 15 formed in the inner end of the shank 7 of the fixed jaw. The adjusting screw 10 is secured to the rod 14 by means of a pin or screw 16. At the inner end of the rod 14 there is a handle 17 providing a means other than the portion 11, having the knurled surface, for rotating the adjusting screw 10.

18 designates the sliding jaw provided with an integral shank 19 having teeth 20 arranged for engagement with the adjusting screw 10. Carried by and preferably formed integral with the shank 19 of the sliding jaw there is a screw driver 21, which is embraced by an extensible coil spring 22 impinging at its one end against the inner end 80 of the shank 19 of the sliding jaw and at its other end upon a projection 23 of the block 12. Said projection is bifurcated in order to permit of a movement of the screw driver 21 beyond the said projection so that 85 the screw driver will project beyond the end of the handle 5 for use.

24 designates a stop formed integral with the shank 19 of the sliding jaw at the innermost or lower end of the rack formed by the teeth 20. This stop 24 is designed to engage with the portion 11 of the screw in order to limit the outward or extended movement of the sliding jaw.

The practical operation of the wrench is 95 as follows: Assuming the parts to be in the positions as illustrated in Fig. 1, it is obvious that the screw 10 can not be moved away from the teeth 20 of the sliding jaw, for the reason that the end of the rod 14 is 100 held in the depressions 15 formed in the inner end of the shank 7 of the fixed jaw; nor can the screw 10 and rod 14 be moved inwardly, because of the engagement between the screw and the teeth 9 of the 105 shank of the sliding jaw. In this condition the wrench may be carried without danger of the screw 10 releasing and permitting the sliding jaw to be moved outwardly. If it be desired to release the jaw, so that it may 110

be moved outwardly by the spring, the screw 10 is turned, either by a manipulation of the portion 11 or the handle 17, thus moving the threads of the screw in a position to cause the spring 22 to move the sliding jaw to a position slightly removed from the fixed jaw. In this position, that is the sliding jaw slightly removed from the fixed jaw, the entire screw 10 may be moved with the rod 14 and shank 19 inwardly to release the end of the rod from the depression 15 permitting a movement of the screw bodily away from the teeth 9 of the shank of the sliding jaw. The spring 22 then causes the jaw 18 to move outwardly. In this outward movement the jaw may be stopped at any desired point by pressing the screw to engage with the teeth 9, or the said movement will be limited by the stop 24 engaging with the portion 11 of the screw, as clearly shown in Fig. 2. By reason of the spring 22 bearing against the projection 23 of the pivoted block above the pivotal center of the block the block and the rod 14 carried thereby will hold the screw 10 in a position normally to engage with the rack of the sliding jaw.

I claim:

1. In a wrench, the combination with a hollow handle, a jaw fixed to said handle, a sliding jaw having a rack arranged for

movement in said handle, a spring for moving said sliding jaw in one direction, a pivoted block acted upon by said spring, a rod carried by said block, a screw carried by said rod and arranged to engage the rack of the sliding jaw, means for manually turning said screw, and a fixed bearing for the end of said rod opposite the end supported in said pivoted block, substantially as shown and for the purposes stated.

2. In a wrench, the combination with a tubular, metallic handle, a jaw fixed in said handle, a sliding jaw having a rack arranged for movement in said handle, a pivoted block, an extensible coil spring acting on said sliding jaw and said pivoted block, a rod carried by said pivoted block and arranged for lengthwise movements relative thereto, a member having a threaded portion for engagement with said rack and a knurled portion for its manipulation secured nonrotatably adjacent the end of said rod, and a fixed bearing in the end of said fixed jaw for the end of said rod.

In testimony whereof, I have signed my name to this specification, in presence of two subscribing witnesses.

ARTHUR CARP.
